UNITED STATES PATENT OFFICE.

VICTOR GUINZBURG, OF NEW YORK, N. Y., ASSIGNOR TO I. B. KLEINERT RUBBER COMPANY, OF NEW YORK, N. Y., A CORPORATION OF NEW YORK.

DESIGN FOR A GARMENT-SHIELD.

56,967.

Specification for Design.

Patented Jan. 25, 1921.

Application filed June 4, 1920. Serial No. 386,596. Term of patent 14 years.

To all whom it may concern:

Be it known that I, VICTOR GUINZBURG, a citizen of the United States, residing in the city, county, and State of New York, have invented a new, original, and ornamental Design for Garment-Shields, of which the following is a specification, reference being had to the accompanying drawing, forming part hereof, in which—

Figure 1 is a front elevation of a garment shield, showing my new design; and Fig. 2 is a rear elevation of the same.

I claim:—

The ornamental design for a garment shield, as shown.

VICTOR GUINZBURG.
